UNITED STATES PATENT OFFICE.

GEORGE WRIGHT, OF SAN FRANCISCO, CALIFORNIA.

BOAT-LAUNCHING APPARATUS.

1,424,227.

specification of Letters Patent. Patented Aug. 1, 1922.

Application filed June 22, 1920. Serial No. 390,935.

To all whom it may concern:

Be it known that I, GEORGE WRIGHT, a citizen of the United States, and a resident of San Francisco, in the county of San Francisco, State of California, have invented certain new and useful Improvements in Boat-Launching Apparatus, of which the following is a full, clear, and exact description.

Among the principal objects which the present invention has in view are: to launch a series of boats from a boat deck of a sea-going vessel simultaneously and in serial order; to automatically dispose a plurality of boats in passenger-loading positions simultaneously, and in superposed spaced relation; to expedite the loading of said life boats in cases of emergency; and to generally expedite the operation of launching a ship's boats.

20 Drawings.

Figure 1 is a plan view of a life boat and launching apparatus therefor, constructed and arranged in accordance with the present invention;

Figure 2 is a side elevation of the same;

Figure 3 is an end elevation of the same, part of the supporting standards being cut away to show the construction otherwise concealed thereby; and

Figure 4 is a schematic view showing the apparatus in its several positions showing the various steps in the handling of the boats.

35 Description.

It has been the custom to nest the boats substantially as shown in Figure 3 of the drawings, the lower boat being disposed in cradles provided therefor, and the superposed boats being disposed within the lower boat. It is obvious that when thus arranged, a sea-going vessel with more or less limited deck space may augment the number of boats usually carried.

Heretofore the boats have been launched successively, the davits and falls connected therewith being employed for hoisting first the uppermost boat to carry it to the passenger-loading position, and subsequently to the launching position, before the falls returned for the second boat, and so on, for the third and fourth boat. It is obvious

that the time consumed in this arrangement is very great, and, in the presence of panic which usually occurs, one or more of the boats are abandoned by the crew.

The present invention provides means for handling all of the boats at one time, while making provisions for the necessary separation of the boats to receive their load, and providing the needed precession of the boats when being disposed in the water, to avoid dangerous collision with each other.

To this end each of the boats designated in the drawings as A, B and C, is attached to separate falls or cables 9, 10 and 11. The cables 9, 10 and 11 are wound on drums 12, 13 and 14, respectively. The drums 12, 13 and 14 have different diameters, the drum 12 being larger than the drum 13, and the drum 13 being larger than the drum 14. The difference in the sizes of the said drums corresponds with the difference in the loading positions of the boats A, B and C, as indicated in Figure 4 of the drawings. That is to say, the distance between the boats A and B, and B and C in the loading positions shown by the full lines in Figure 4, corresponds with the differences in the circumferences of the said drums, when and as the same are lowered from the outboard position to which they are lifted, and moved by the swing of the davits 15. Due to the greater peripheral speed of the drum 12, the cable 9, which is wound on the said drum, carries the entire burden of the nested boats A, B and C, when the boats are lifted from the cradle 16 on which they are stowed in the inactive position.

The davit 15 is manipulated to automatically swing inboard or outboard by a mechanism set forth in an application for improvements in boat launching apparatus filed by me, the 24th day of September, 1919, 95 bearing Serial No. 326,031 and to which application cross reference is here made. It will be understood that any of the cables 9, 10 or 11, may be utilized for operating the tripping mechanism described in the application above referred to.

The drums 12, 13 and 14 are preferably integrally or rigidly connected. They are mounted on a shaft 17, which is driven by an electric motor 18. Both ends of each of the cables 9, 10 and 11 are attached to the re-

spective boats, and at the opposite ends thereof in hooks or eyelets, such as usually are provided. The extensions of the said cables are carried from the said drums in 5 relatively opposite directions, one extension being paid off at the top of the drum with which it is associated, while the other extension is paid off at the bottom of the said drum, with the result that the said extensions move in relatively opposite directions when approaching or leaving the drum. Uniformity of movement of the ends of the respective boats is thereby assured.

The various cables 9, 10 and 11, are carried by pulleys 19, 20 and 21 to the blocks 22 at the top of the davits 15. As seen in Figure 2 of the drawings, the cable 11 is extended through the shiftable guide block 23, which is more fully described in the application above referred to. The pins 24 may be withdrawn from the blocks in the position shown in Figure 2, and transferred to the holes 25 in the lower extremity of the davits 15, when it is desired to move the davits to the outboard or active operating position of the same. The result of moving the block 23 to the upper or lower position provided for the said blocks is set forth in the application referred to.

It has not been thought necessary to show the electric source and circuit utilized for operating the motor. It will also be understood that the arrangement disclosed in the application above referred to with reference to the group handling of the launching device for the single boats will be employed when a vessel is equipped with the apparatus here disclosed for handling a plurality of boats by the same apparatus.

In the operation of the apparatus the motor 18 is first employed for lifting the boats A, B, and C, from the cradles 16. As explained, the weight of the entire group of boats will be borne by the cable 9, due to the fact that the larger circumference of the drum 12 takes up more of the cable with which it is associated than do the drums 13 and 14.

The boats being free of the cradles, the davits 15 are swung outboard, as shown in Figure 4 of the drawings. In this position of the davits, the motor 18 is reversed and the boats are lowered to the position shown in full lines, which, as indicated, places the various boats opposite the various decks where they are to receive the passengers.

In paying out the cables 9, 10 and 11, the drums 12, 13 and 14 operate as in the ratio established by the relative circumferences of the said drums. As seen, the boat C is supported by the cable 11, which is paid out from the relatively small drum 14, and therefore in the given time only passes to the upper loading deck. In the same space of time, the drum 13 pays out sufficiently

more of the cable 10 to dispose the boat B opposite the second deck, while the drum 12 is paying out sufficient of the cable 9 to dispose the boat A opposite the lower deck. These positions being maintained, the motor 18 is arrested, and holds the apparatus while the various boats are receiving the passengers and crew. This having been accomplished the motor 18 is again actuated to pay out the various cables, when again the difference in the size of the drums effects further separation of the boats A, B and C. As shown by broken lines, the position of the boat B is sufficiently above the boat A, when the latter reaches the water, 80 to avoid being struck thereby when lifted by a wave.

The motor 18 may be arrested in this position, or continued to operate as experience shall deem expedient, the idea being that sufficient time shall be allowed to clear the boat A from the vessel to give space for the boat B when it arrives at launching position. Both boats are cleared away from the vessel as rapidly as possible, to allow the boat C to be launched, which is accomplished by the continuation of the operation of the motor 18.

It will be understood that when the boats are returned to the ship, they are hoisted in the serial manner indicated.

Claims.

1. An apparatus as characterized comprising a plurality of boat handling davits; means disposed between said davits for supporting a group of boats in nested relation; a plurality of cables each attached to one of said boats; and a hoisting mechanism for operating said cables simultaneously at various fixed ratios to raise and lower said boats in groups.

2. An apparatus as characterized comprising a plurality of boat handling davits; means disposed between said davits for supporting a group of boats in nested relation; a plurality of cables each attached to one of said boats; and a hoisting mechanism for said cables embodying a plurality of drums, each drum engaging one of said cables simultaneously to wind said cables at various fixed ratios for operating said boats in groups.

3. An apparatus as characterized comprising a plurality of boat handling davits; means disposed between said davits for supporting a group of boats in nested relation; a plurality of cables each attached to one of said boats; and a hoisting mechanism for said cables embodying a plurality of drums, each drum engaging one of said cables to wind said cables at various rates for operating said boats at various speeds, said drums being rigidly connected for operation simultaneously.

4. An apparatus as characterized comprising a plurality of boat handling davits; means disposed between said davits for supporting a group of boats in nested relation; a hoisting mechanism embodying a plurality of cables, each attached to one of said boats, a plurality of drums, each
- drum engaging one of said cables, and a driving mechanism for said drums for winding said cables simultaneously at various 10 fixed ratios for operating said boats at relatively different speeds.
